ELECTRICAL CONTROL

Richard M. Somers, West Orange, N. J., assignor
to Thomas A. Edison, Incorporated, West
Orange, N. J., a corporation of New Jersey

Application May 11, 1939, Serial No. 272,937

10 Claims. (Cl. 175—335)

This invention relates to electrical control, and more particularly to such control of the position of a movable system—which may be a system, itself of any nature, which it is desired to move selectively between two positions.

It is a general object of the invention to provide a novel, improved and simplified control of the type described.

An electrical control for a movable system as above-mentioned was disclosed in the co-pending application of myself and Charles T. Jacobs, Serial No. 266,338, filed April 6, 1939. In that control there were employed electromagnetic means for provoking the movement of the movable system in its two directions and a switch or control means operable to supply alternately to the electromagnetic means actuating currents at two different voltages, the electromagnetic means being voltage-controlled so as to maintain the movable system in step with the control means; a common conductor for the two respective actuating currents was employed. It is an object of the instant invention to provide a control of very generally similar character, but simplified and improved thereover.

In the co-pending application abovementioned the electromagnetic means comprised a pair of electromagnetic devices together with means for alternating the supply of actuating current thereto. An object of the instant invention is to provide an effective control of the type described operable without alternation of the supply of actuating currents to respective electromagnetic means.

Another object is to provide a control of the type described wherein two appropriate electromagnetic devices are combined in a single unit, with attendant reduction of complexity and cost.

Other and allied objects will more fully appear from the following description and the appended claims.

In the description of the invention hereinafter set forth reference is had to the accompanying drawing, in which:

Figure 1 is a schematic diagram of a control embodying my invention in one form, certain parts being illustrated in elevation and the solenoid 12 in cross-section; and

Figure 2 is a similar diagram of a control embodying my invention in a modified and somewhat simplified form.

In the illustration of my invention I have shown a movable system comprising a lever 1, pivoted as at 1' and rockable for example between stationary stop members 2. The lever 1 may serve

5 to control any desired device 4, this having been wholly schematically illustrated in the drawing. Purely as an example, the device 4 may be a clutch for other apparatus, movable between engaged and disengaged positions by the movement of the lever 1.

For provoking movement of the lever 1 between its two positions there has been illustrated an electromagnetic assembly comprising as one electromagnetic device a solenoid 12 and plunger 14 therefor, and as another electromagnetic device an electromagnet 11 and armature 13 therefor. A connection is provided between the plunger 14 and the lever 1, so that axial movement of the plunger rocks the lever. This connection may for example be a pivotal one; it may be desirable in certain instances, however, that it also be a yieldable one, and I have illustrated it as provided by an aperture 14a in the enlarged flattened 10 righthand end portion 14b of the plunger, by a pin 1c extending forwardly from the upper portion of the lever 1 through the aperture 14a, and by a spring 18 tensioned from the forward end of pin 1c to a pin 14c extending forwardly from 15 the plunger end portion 14b to the left of the aperture 14a—the spring 18 serving to urge the pin 1c against the lefthand end of the aperture 14a. The plunger 14 is biased to a righthand or "first" position, wherein its major portion is withdrawn from the coil 12c of the solenoid; by way 20 of example, a biasing means has been shown as the expansion spring 5 disposed axially within the coil 12c between the lefthand plunger extremity and a screw 5a adjustable in a bracket 5b 25 at the lefthand solenoid extremity. This righthand plunger biasing of course biases the movable system, or lever 1, righthandward; and a stop for righthand movement of both plunger and system is of course provided by the righthand stop 30 member 2 abovementioned.

It will be understood that upon actuation of the solenoid 12 the plunger 14 will be subjected to leftward movement, for example to a point where the spring 5 is fully compressed. The components 45 are so apportioned that this leftward plunger movement will be sufficient, and preferably at least somewhat more than sufficient, to move the lever 1 into its "second" position, of contact with the lefthand stop member 2; the additional 50 plunger movement over that sufficient for full lever movement, or "overshooting" by the plunger, may be automatically taken up in the yielding of the connection between the plunger and the lever 1—i. e., in expansion of the spring 18 abovementioned.

Secured to and extending downwardly from the end portion 14b of the plunger 14 is a lug 16; and underneath the plunger is provided a latch for engaging this lug, and so retaining the plunger, when the plunger has been moved leftwardly as 5 above-mentioned. The latch proper is shown as 15, formed upwardly from the righthand extremity of a latch member 15a; this member is pivoted at its lefthand extremity, and is biased upwardly to a normal horizontal position, of contact 10 with the bottom of a stationary stop member 19, as by a strong spring 17. The armature 13 above-mentioned is secured to the bottom of and is carried by the latch member 15a; and below the armature, spaced therefrom when the latch member 15 15 is in normal position, is the pole tip 11' of the electromagnet 11 above-mentioned.

With the electromagnet 11 unactuated and the latch member 15a accordingly in its normal position, the latch 15 lies in the horizontal path 20 of lug 16; and that lug, if to the left of the latch, will be retained thereby. The components are preferably so apportioned that when the lug is in its position of retention by the latch (indicated in dash-dot lines as 11c) the lever 1 will be held in its second position with negligible expansion of spring 18; the complete leftward plunger movement, above-mentioned as occurring upon solenoid actuation and as preferably involving some yielding of the plunger-lever connection, may cause the lug to overshoot that position of retention (for example to the position indicated as 11c), the lug returning to the position of retention (11) upon cessation of the solenoid actuation. When the electromagnet 11 is thereafter actuated the armature 13 will be attracted to the pole tip 11', the latch member 15a will be rocked downwardly, and the latch 15 will release the lug 16—i. e., will be brought down wholly out of the horizontal path of the lug. Thereupon of course the lug 16 and plunger 14 will move rightwardly under the force of spring 5 to rock the lever 1 into its first (illustrated) position; thus a temporary actuation of the electromagnet 11 alone is sufficient to provoke a movement of the movable system from its second to its first position. And if the righthand extremity of the latch 15 be bevelled, as has been illustrated by way of example, a temporary actuation of the solenoid 12 alone would be sufficient to move the plunger leftwardly and bring the movable system from its first to its second position; the lug 16 in its leftward movement would cam the latch out of its path, the latch immediately returning under the influence of its biasing spring 17.

It follows that the movable system may be alternately moved between its two positions by alternate actuations of the solenoid 12 and the electromagnet 11. It is permissible, however, that each actuation of the solenoid 12 be accompanied by an actuation of the electromagnet 11—in other words, that each leftward attraction of the plunger 14 be accompanied by a releasing movement of the latch 15—provided the apparatus is arranged so that upon cessation of the joint actuation the latch will return toward normal position at least sufficiently to catch the lug 16 before the lug, in its rightward movement under the force of spring 5, has passed the latch. The apparatus is readily so arranged, for example, by making sufficient the distance of overshooting by the plunger and lug of the position of retention above-mentioned, or by rendering small enough (relative to the effective

mass of the plunger 14 and components moved therewith) the effective mass of the armature and latch and latch member 13—15—15a, or by rendering strong enough the spring 17, or by two or all of these expedients. Accordingly I have shown the aperture 14a large enough, and the apparatus otherwise suitably apportioned, to accommodate a substantial overshooting by plunger and lug, and I have shown the armature and latch and latch member (of which the latter two may be of a material of relatively low specific gravity) as of quite small dimensions and maximum radius about their pivoting point.

To provide most simply an alternation of actuations of (a) both solenoid 12 and electromagnet 11 and (b) electromagnet 11 only, I may connect the coils (12c and 11c, respectively) of these devices together for joint current supply thereto, and may alternately supply thereto currents (a) at a voltage sufficient for actuation of both solenoid and electromagnet and (b) at a voltage sufficient only for actuation of the electromagnet. This involves arranging the solenoid 12 so that it will be actuated—i. e., energized in sufficient degree to subject plunger 14 to the leftward movement above-mentioned—by current only at the higher of two voltages, the electromagnet 11 being actuatable (to attract armature 15) by current either at that higher or at a lower voltage. Purely as an example of a means for rendering the solenoid actuatable only as stated, there has been illustrated in series with its coil 12c a resistance 10; but it will be understood that the means may consist in any element or elements in or associated with the solenoid, such as the solenoid coil itself (12c), then wound for ineffectiveness when supplied with current at only the lower voltage.

It will be understood that the currents are supplied at two voltages, one of which exceeds a predetermined value, and the other of which is substantially less than that value—the predetermined value being for example that which is just sufficient to cause the force developed by the solenoid to counterbalance that of the plunger-biasing spring 5.

With the illustrated arrangement it is appropriate that the actuating currents supplied to the solenoid and electromagnet be momentary currents—i. e., of restricted duration—which is of course highly desirable for the avoidance of wasteful continued current flows, overheating of the coils 12c and 11c, and the like. The means for supplying these actuating currents may comprise a current source 20, a control switch S hereinafter described, and conductor means connecting them together and with the interconnected coils 12c and 11c. Thus one terminal of the source 20 may be connected to the control switch S through the conductor 21. The other terminal of the source 20 may be connected to the control switch S through the conductor 22, in which the electromagnetic means is serially connected to be controllably supplied with current; in other words, the conductor 22 may be considered as broken, and the ends produced by the break respectively connected to terminals A and B of the paralleled coils 12c and 11c.

The control switch S may be of a form such as described and claimed in my co-pending application Serial No. 252,523, filed January 24, 1939. In general, it comprises two serially arranged portions; the function of one portion is to select between a direct circuit closure and closure through a voltage-limiting device, while

the function of the other portion is to complete momentarily the selected closure.

The first portion of the switch S may typically comprise a switch pole 35 pivoted as at point 31', extending therefrom generally upwardly to be thrown in an arc between stationary stop members 36, and carrying a contact button 35a in its right-angularly twisted upper end portion 35b; and two contact springs 41 and 42, with respective contact points 41a and 42a, adapted to be contacted by button 35a when the pole 35 is respectively in its first (righthand) and second (lefthand) positions. The second portion of the switch S may comprise a switch pole 31 pivoted at the same point 31' (and thus electrically connected with pole 35 abovementioned), and extending therefrom generally downwardly to be thrown in a somewhat smaller arc between stationary stop members 33; and a stationary contact 30 passed over and temporarily contacted by pole 31 in each of the throws of that pole. Pole 31 is toggled to the pole 35 as by spring 34 tensioned between pins 31a and 35a' extending forwardly from intermediate points on the respective poles, the pole 31 thus being thrown in response to each throw of pole 35. Pole 35 may be thrown directly or in any convenient manner; by way of example there has been shown a rod 37 pivotally secured to pole 35 and passing leftwardly therefrom through an aperture 38' in panel 38, to terminate in a knob 40 which may be pushed and pulled toward and away from the panel to throw the pole. Pole 35 may be subjected only to the bias of the toggle spring 34 urging it to retain each of its two positions, or if desired may be biased into a predetermined one of those positions by a sufficiently strong spring 39.

Conductor 21 may be connected to contact 30; conductor 22 may be connected to spring 42 directly, and to spring 41 through the voltage-limiting resistance 25 bridged between the springs. The springs 41 and 42 are arranged so that as pole 35 is moved toward either spring, that spring will be contacted by the pole materially before the pole reaches its extremity of movement in that direction, the spring flexing as that movement is completed. Accordingly as the pole 35 is moved leftwardly from its first (illustrated) position to its second position, it will first quit contact with the spring 41, next make contact with spring 42, and finally—when the toggle spring 44 has been carried just past the pivoting point 31'—will cause the leftward throw of the pole 31; the momentary closure of pole 31 against contact 30 will now cause the supply through conductor 22 of a current pulsation at the full voltage of the source 20 (i. e., free of any limitation by the voltage-limiting resistance 25). Conversely, as the pole 35 is moved from its second to its first position, it will first quit contact with the spring 42, next make contact with the spring 41, and finally will cause the rightward throw of the pole 31; in this instance the momentary closure of pole 31 against the contact 30 will cause the supply through conductor 22 of a current pulsation at a voltage limited by the resistance 25. The duration of the current pulsation supplied on each throw of the control switch is of course determined by the duration of the contact of 31 with 30; this may be predetermined at desired value by apportionment of the length of the contact 30 in the direction of the throw, the tension of spring 34, and the effective mass of pole 31—the latter being regulable as by suit-

able weighting of its extremity, indicated as 32. It will be understood that the higher- or full-voltage current pulsation supplied on leftward throw of the switch S will be effective to actuate both the solenoid 12 and the electromagnet 11; the solenoid actuation will attract the plunger 14 leftwardly and move the movable system to its second position. The electromagnet actuation will move the latch 15 downwardly to its release position, but immediately at the cessation of the pulsation the latch will fly back into its normal position—in time, as above explained, to catch the plunger lug 16 and thus to hold the movable system in its second position. It will further be understood that the lower- or limited-voltage current pulsation supplied on rightward throw of the switch S will be effective to actuate only the electromagnet 11; the latch 15 will be moved downwardly to release the plunger lug 16, and under the influence of spring 5 the plunger will move rightwardly and will carry the movable system to its first position. The supply to the solenoid of the reduced current, although this is insufficient for movement of the plunger leftwardly against the force of spring 5, will operate to reduce the effective rightward bias of the plunger and hence the lug pressure against the latch 15, thereby facilitating the releasing or disengaging movement of the latch.

In the system as so described the movable system is very effectively constrained into step, and maintained in step, with the control means. Thus upon supply of the full-voltage current it is impossible for the movable system to be placed in its rightward or first position; the solenoid 12 keeps the plunger in its most leftward position for so long as the latch is in release position, and so prevents the latch release from having any actual effect on the plunger. And upon supply of the reduced-voltage current it is impossible for the movable system to be placed in its leftward or second position; the weakness of the solenoid energization prevents its having an effect on the plunger any more than partially counteractive of the rightward biasing force of spring 5. Although there are thus maintained predetermined positional and motional relationships between the movable system and the control switch, it is conceivable that on some occasion this relationship will be reversed, as by some ill-advised, purely mechanical manipulation of one or more of the components. The system will be seen, however, to restore the predetermined relationship upon the very first throw of the switch S following such a reversal.

In the embodiment illustrated in Figure 1 separate electromagnetic devices are employed for provoking the respective movements of the movable system; my invention, however, is not limited to such a separation, and in Figure 2 I have illustrated an embodiment wherein these devices are combined into a single unit. In this embodiment there may again be employed the control switch S and the movable system comprising lever 1, and their first and second positions may be considered respectively the same as in Figure 1. The solenoid 12 and its plunger 14 may also again be employed; but by way of alternative illustration the expansion spring 5 of Figure 1 immediately effective on the plunger 14 has been replaced by a tension spring 6 immediately effective on the lever 1 (spring 18 preferably being appropriately strengthened so that it still expands only after the lever 1 has reached its lefthand or second position). At the left-

hand end of the solenoid 12, and extending a short distance inwardly of the solenoid, there is secured a short pole member 111; and this pole member, together with the coil 12c of the solenoid, is employed in replacement of the electromagnet 11 of Figure 1. While an armature, latch, latch member and plunger lug are again employed for their former functions, such elements are shown in a re-arrangement appropriate to the modified construction. Thus the latch member 115a (preferably, like member 15a, light and small) may be of inverted L-shape, pivoted in the region of its angle and carrying the armature 113 near the lower extremity of its vertical leg, opposite the pole 111; a normal spacing of armature from pole may be effected by spring 117 biasing the latch member 115a clockwise into contact with stationary stop member 119. The latch proper, 115, is formed downwardly from the righthand extremity of the horizontal leg of the member 115a, above the solenoid 12. The plunger lug, 116, is now formed upwardly from the lefthand extremity of a horizontal rod 116a, from whose righthand extremity a connecting arm 116b extends downwardly to be secured to the plunger end portion 14b so that the lug is again effectively carried by the plunger.

In Figure 2 the control switch S has been purely schematically illustrated, in view of its permissible identity with that of Figure 1. The terminals A and B of the electromagnetic means are simply the terminals of the coil 12c. No special resistance such as 10 has been illustrated in Figure 2; the components, including the coil 12c and the springs, are simply so apportioned that while either the full- or reduced-voltage current supply will move the armature 113 (i. e., effectively actuate the electromagnetic device which includes the armature), only the full-voltage current supply will move the plunger and movable system leftwardly (i. e., effectively actuate the electromagnetic device which includes the plunger). A yieldable bumper or stop for leftward plunger movement may if desired be provided, having been shown as the felt or like button 108 secured to the righthand extremity of the pole 111.

The operation of the embodiment of Figure 2 is fundamentally similar to that of the embodiment of Figure 1. Thus upon supply of the higher- or full-voltage current pulsation the plunger 14 will be moved leftwardly, into contact for example with the stop 108; under this condition the lug 116 will be in a position (such as indicated at IIa) spaced at least slightly leftwardly from the latch 115, the lever 1 will be in second (leftward) position, and the spring 18 will be somewhat expanded. The latch 115 will of course be raised out of the path of the lug simultaneously with the plunger movement, but upon termination of the current supply the latch will immediately drop down into that path; it will then retain the lug in the position indicated as II, with the plunger somewhat spaced from the stop 108 and with the lever 1 still in second position. Upon supply of the reduced- or lower-voltage current pulsation the latch will be raised to release the lug; the energization of the solenoid is, however, insufficient fully to counterbalance the force of spring 6, and the plunger and movable system will move rightwardly to first position under the influence of that spring.

It will be understood that the term "energization" is used in connection with the production

of any force by the solenoid or other device, and the term "actuation" only in connection with the production of an actual movement-effecting force.

5 While I have disclosed my invention in terms of two particular embodiments thereof, I do not intend that all its aspects be limited by details of those embodiments, which obviously may be widely varied without departure from the true 10 spirit and scope of the invention. In some of the appended claims I undertake to express that scope broadly, subject however to such proper limitations as the state of the art may impose.

I claim:

15 1. In an electrically operable control, the combination of a biased member; means actuatable by current only at voltage exceeding a predetermined value for moving said member against its bias; a latch for holding said member moved against its bias; means, actuatable by current at voltage substantially less than said predetermined value, for moving said latch for release of said member; and a pair of electrical terminals common to said member-moving and latch-moving means whereby current is supplied to them jointly.

20 2. In an electrically operable control, the combination of a biased plunger; a solenoid actuatable by current only at voltage exceeding a predetermined value for moving said plunger against its bias; a latch for holding said plunger moved against its bias; electromagnetic means, actuatable by current at voltage substantially less than said predetermined value, for moving said latch for release of said plunger; and a pair of electrical terminals common to said plunger-moving and latch-moving means whereby current is supplied to them jointly.

25 3. In an electrically operable control, the combination of a member biased to a first position; a latch for holding said member in a second position displaced from said first position against the bias of the member; means actuatable by current only at voltage exceeding a predetermined value for moving said member from its first to beyond its second position; means, actuatable by current at voltage substantially less than said predetermined value, for moving said latch for release of said member; and a pair of electrical terminals common to said member-moving and latch-moving means whereby current is supplied to them jointly.

30 4. The combination according to claim 3, further including a system having a connection with said member and movable between limiting positions by the movement of said member between its said first and second positions, and yielding means included in said connection for permitting the movement of said member beyond its said second position.

35 5. In an electrically operable control, the combination of a biased member; an electromagnetic device actuatable by current only at voltage exceeding a predetermined value for moving said member against its bias; a latch for said member; and an electromagnetic device actuatable by current at voltage substantially less than said predetermined value for operating said latch, said electromagnetic devices having a common coil.

40 6. In an electrically operable control, the combination of a biased plunger; a solenoid actuatable by current only at voltage exceeding a predetermined value for moving said plunger against its bias; a latch for said plunger; and an electromagnet actuatable by current at voltage substantially less than said predetermined value for oper-

ating said latch, said solenoid and electromagnet having a common coil.

7. In an electrically operable control, the combination of a biased plunger; a solenoid, comprising a coil, for moving said plunger against its bias; a latch for holding said plunger moved against its bias; a pole associated with said coil and forming therewith an electromagnet; and means, including an armature positioned for attraction by said pole, for rendering said latch responsive to said electromagnet.

8. In an electrically operable control, the combination of a biased member; means actuatable by current only at voltage exceeding a predetermined value for moving said member against its bias; a latch for holding said member moved against its bias; and means, actuatable by a momentary current impulse at voltage substantially less than said predetermined value, for moving said latch for release of said member, said latch-moving means being connected with said member-moving means for joint energization therewith.

9. In an electrically operable control, the combination of a member biased to a first position and movable therefrom to and beyond a second position; a latch, biased to member-engaging position, for holding said member in said second position; means actuated only by current supply at voltage exceeding a predetermined value to move said member to beyond said second position; and means concomitantly actuated by the same current supply to move said latch out of member-engaging position, said member being

responsive to its bias upon cessation of said current supply to move to its second position, said latch being more rapidly responsive to its bias upon said cessation to move to member-engaging position, and said second-mentioned means being also actuatable by current supply at voltage less than said predetermined value to move said latch out of member-engaging position, whereby to permit said member to move to said first position in response to its bias.

10. In an electrically operable control, the combination of a member biased to a first position and movable therefrom to and beyond a second position; a latch, biased to member-engaging position, for holding said member in said second position; means actuated only by current supply at voltage exceeding a predetermined value to move said member to beyond said second position; and means concomitantly actuated by the same current supply to move said latch out of member-engaging position, said member being responsive to its bias upon cessation of said current supply to move to its second position, said latch being more rapidly responsive to its bias upon said cessation to move to member-engaging position, and said second-mentioned means being also actuatable by a momentary current supply at voltage less than said predetermined value to move said latch out of member-engaging position, whereby to permit said member to move to said first position in response to its bias.

RICHARD M. SOMERS.
